ATTORNEY

UNITED STATES PATENT OFFICE

CHARLES T. GILBERT, OF SAGINAW, MICHIGAN, ASSIGNOR TO SAGINAW MANUFACTURING CO., OF SAGINAW, MICHIGAN, A CORPORATION OF MICHIGAN

FOLDING IRONING TABLE

Application filed May 31, 1930. Serial No. 457,912.

This invention relates to ironing tables and particularly to that class of tables adapted for the ironing of small articles, the ironing table being of small size and arranged, when 5 in use, to stand on an ordinary table.

The present improvement relates more specifically to the construction and arrangement of the three legs and their cooperating connecting rods and pivoted joints.

10 The objects attained by the claimed combination are as follows:

To provide an ironing table of the class described that embodies simplicity, cheapness of construction, has few moving parts, 15 those being arranged to co-operate so that when opened for use the table legs are rigidly interlocked against rocking or collapsing. A further object is to provide a structure for the two end legs such that they will, 20 when upright, form a strong support bearing directly against the ironing board and extending to the surface upon which the ironing table stands. Thus the two end legs are made capable of supporting heavy pressure, 25 sure loads on the ironing board without bringing strain or wear upon any of the leg pivots or jointed connections.

Another object is to provide a supporting structure for an ironing board that includes 30 legs connected together by rods in such a way that lifting any one of the three legs from its folded position will automatically lift all the other legs and will establish them in mutually interlocked position for ironing.

35 In the drawings Fig. 1 is a view of the under side of a preferred embodiment of the invention, showing the legs folded.

Fig. 2 is a fragmentary end view with legs upright.

40 Fig. 3 is a side view of the board shown in Fig. 1, partly broken away to show the remote leg as it appears when viewed in the direction of the arrows, Fig. 2.

According to the construction illustrated 45 in Figs. 1, 2, 3, the main part of the leg, 5, is short enough so that in upright position its top end is spaced down from the cross bar 2, as indicated at X in Fig. 2. In this construction a plate 6 is fixed to a side of the 50 leg 5, by the pivot pin 4. At its lower end

the plate 6 has a laterally projecting flange 6b. The flange is received in a transverse mortise 5a, located on the side of the leg opposite the flange 3 of cross bar 2.

The upper end of the plate is shaped at 55 6a to make contact with the face of the cross-bar when the leg is upright. Since leg 5 and plate 6 together form a rigid support for the board 1, as above described, the pivot 4 is not subjected to any bending or wearing 60 strains when the board is heavily loaded.

In the structure shown in Fig. 3, the moving of either of the legs 5, or leg 9, in the direction of the arrows will cause all of the legs to fold flat against the under side of 65 the board as shown in Fig. 1.

When the legs are in use, as in Figs. 2 and 3, they are firmly locked in position by reason of the connection of rod 7 with the leg 9 below the hinge 8, and with legs 5 above the 70 pivot 4.

Having thus described my invention, what I claim and desire to secure by Letters Patent is:

1. In combination, an ironing board having secured to its under side near one end a cross bar with downwardly projecting end flanges, a pivot pin near the lower end of each flange, a leg pivoted near its upper end on said pin, the top of the leg, when in upright position, spaced downwardly from said cross bar, a leg-actuating plate secured to the leg by the pivot pin, the upper end of said plate being shaped to contact with said cross bar when the leg is in upright position, 80 said plate having at its lower end a laterally projecting flange received in a transverse mortise formed in that side of said leg which is opposite the flange of said cross bar, a leg-actuating rod having an end pivoted to said plate near a corner thereof remote from said pivot pin, a hinge secured to the under side of the board near the middle, a leg secured to a leaf of said hinge, said leg-actuating rod pivoted at its other end to said last mentioned 85 leg adjacent said leaf.

2. In combination, an ironing board having a cross bar with downwardly projecting end flanges, a pivot pin secured to each flange, a leg pivoted on each pin, the leg, when 100

upright, having its top end spaced downwardly from said cross bar, a plate rigidly fixed to the leg, the upper end of said plate projecting beyond the end of the leg and being shaped to contact with said cross bar when the leg is upright, a leg-actuating rod having an end pivoted to said plate, a hinge secured to the under side of the board near its middle, a front table leg secured to a leaf 10 of said hinge, said leg-actuating rod pivoted at its other end to said last mentioned leg adjacent said leaf.

In testimony whereof, I affix my signature.

CHARLES T. GILBERT.
